UNITED STATES PATENT OFFICE

JOHN STANLEY STULL, OF CHICAGO, ILLINOIS, ASSIGNOR TO WESTERN ELECTRIC COMPANY, INCORPORATED, OF NEW YORK, N. Y., A CORPORATION OF NEW YORK

APPARATUS FOR STRIPPING COVERED STRANDS

Application filed April 10, 1926. Serial No. 101,042.

This invention relates to apparatus for stripping covered strands, and more particularly to apparatus for stripping insulated electrical conductors.

5 The object of this invention is to provide an apparatus for stripping the coverings of continuously covered strands for predetermined lengths and at predetermined points throughout their length with speed, accuracy and a minimum of attention.

In accordance with one embodiment of this invention, as applied to an apparatus for skinning the insulation on electrical conductors, there is provided a drum revolving 15 at a uniform speed which carries a plurality of clamping and cutting devices operated at predetermined points in the movement of the drum to successively clamp a pair of twisted conductors drawn from a supply reel to the 20 drum and sever the insulation of the conductors at diametrically opposite points thereof.

A stationary cam member causes a movement of the operative cutting device in a direction reverse to that in which the drum is 25 moving while the conductors which are clamped to the drum are advanced, thus moving the insulation back along the conductor cores for a predetermined distance and exposing the bare cores. Thereafter the 30 cutting device is released and disengaged from the conductors which are finally unclamped from the drum and wound upon a take-up reel rotated in synchronism with the drum and simultaneously moved bodily in a 35 longitudinal direction to wind them in even layers upon the reel.

Other objects and advantages of this invention will more fully appear from the accompanying detailed description taken in 40 connection with the accompanying drawings which illustrate one embodiment thereof, in which

Fig. 1 is a fragmentary plan view of a conductor stripping apparatus embodying the features of this invention;

45 Fig. 2 is an enlarged fragmentary sectional view taken upon the line 2—2 of Fig. 1 looking in the direction indicated by the arrows;

50 Fig. 3 is a detail vertical sectional view

taken upon the line 3—3 of Fig. 2 looking in the direction indicated by the arrows;

Fig. 4 is an enlarged detail vertical sectional view taken upon the line 4—4 of Fig. 3 looking in the direction indicated by the 55 arrows showing the conductors at the completion of the insulation severing operation;

Fig. 5 is a view similar to Fig. 4 only showing the insulation moved back at the completion of the insulation stripping operation 60 and exposing the cores;

Fig. 6 is an enlarged detail horizontal sectional view taken upon the line 6—6 of Fig. 2 looking in the direction indicated by the 65 arrows;

Fig. 7 is a detail horizontal sectional view taken upon the line 7—7 of Fig. 2 looking in the direction indicated by the arrows, and

Fig. 8 is a view of a pair of twisted insulated conductors as delivered from the apparatus.

As shown in the accompanying drawings, the apparatus is supported upon a base plate 10 having arranged thereon at the left end (Fig. 1) a supply reel 11 carrying in the particular embodiment illustrated, a supply of insulated electrical conductors 12 which are to be bared for a predetermined distance and at predetermined points therealong, the conductors being arranged in pairs having a 80

comparatively long twist (Fig. 8). The supply reel 11 is rotatably supported upon an overhanging rotatable arbor 13 (dotted outline Fig. 1) in turn carried upon an upright standard 14 provided with a pair of spaced journals 17 and 18. Fixed to the arbor 13 between one head of the reel 11 and the journal 17 is a collar 19 and surrounding the arbor 13 between the journals 17 and 18 is a compression spring 20, an anti-friction collar 21 being carried free upon the arbor 13 between one end of the spring 20 and the journal 17 with a collar 24 carried upon the arbor 13 and abutting the opposite end of the spring 20. The reel 11 is secured to the arbor 13 by a hand nut 25 screw threaded upon the arbor 13, the nut 25 serving to clamp the reel 11 against the collar 19 which is fixed to the arbor 13. It will be apparent that upon adjustment of the collar 100

24 to suitably compress the spring 20, sufficient friction will be maintained between the collar 19 and the journal 17 to provide a sufficient drag upon the reel to prevent over-
5 running thereof during operation of the apparatus.

Intermediate the supply reel 11 and a take-up apparatus 26, to be described in greater detail hereinafter, is a base plate 27 having
10 a pair of spaced upright standards 28 and 29 provided with journals 31 and 32 respectively, rotatably supporting a shaft 33, the shaft being driven in a counter-clockwise direction at a predetermined uniform speed through a
15 suitable source of power (not shown). Rotatably carried upon a pair of stationary studs 34 fixed to the standards 29 upon a horizontal plane above the axis of the shaft 33 and equally spaced therefrom is a pair of
20 grooved guide rollers 35 (Figs. 1 and 2). Fixed for rotation with the shaft 33 intermediate the standards 28 and 29 is a drum or cup-shaped wheel 38 (Fig. 7) provided with a continuous peripheral groove 39, which is in line with the grooved rollers 35 (Fig. 1). Carried by the wheel 38 is a plurality of
25 spring pressed plungers 40 (Fig. 7) which are actuated at predetermined points in the rotation of the wheel 38 to cause the conductors
30 to be gripped within the groove 39 by a stationary face cam 41 (Figs. 1 and 7) secured to the standard 29. The plungers serve to grip the wires to the wheel 38 during the rotation thereof, as will be explained more fully
35 in the description of operation of the apparatus. The plungers 40 are each actuated through the movement of a sleeve 42, the upper end of which (Fig. 7) carries a button 43 arranged to ride upon the cam 41. Mounted
40 between the sleeve 42 and the end wall of the depression in the wheel 38 within which the sleeve is adapted to reciprocate is a compression spring 46. The plunger 40 is provided with a head 47 having a sliding fit within the
45 bore of the sleeve 42 and carried within the sleeve between the head 47 and the button 43 is a second compression spring 48 through which the movement of the sleeve 42 is transmitted to the plunger 40 to cause the gripping
50 of the conductors as shown in Fig. 7. Upon the button 43 riding onto the low point of the cam 41 the compression spring 46 serves to positively free the plunger 40 from the conductors, the spring being compressed during
55 the gripping of the conductors as will readily be apparent. Due to the spring 48 intermediate the button 43 and the head 47 of the plunger 40 it will be apparent that any slight variation in the diameter of the conductors
60 to be stripped will be compensated for by the yielding of the spring. Formed in the peripheral wall of the cup-shaped wheel 38 at diametrically opposite points are slots 49 and
65 50 which extend from the forward end of the

wheel 38 to a vertical inner wall 53 thereof (Figs. 2 and 7).

Mounted upon the shaft 33 within the cup-shaped wheel 38 is a pair of nested knife holders 54 and 55 with a shouldered end 56 of each arranged to slide upon one face of the slots 49 and 50. The holders are each provided with elongated openings 57, the narrow portion of which is substantially the same width as the diameter of the shaft 33, thereby permitting a movement of the holders toward the periphery of the wheel 38 at predetermined intervals in the rotation of the wheel. The holders 54 and 55 are each normally urged inwardly toward the axis of the wheel 38 by compression springs 60 housed within openings formed in the inner ends thereof (Figs. 2 and 3), the springs at one end thereof engaging the periphery of the shaft 33 with the opposite end engaging an adjustable set screw 61. The shouldered end 56 of each of the knife holders is normally held in engagement with its associated face of the slots 49 and 50, as clearly indicated in dotted outline on Fig. 2, by a spring pressed plunger 62 mounted in a supporting housing 63 in turn carried upon the inner vertical wall 53 of the wheel 38. In the counter-clockwise rotation of the wheel 38 the knife holders 54 and 55 are in turn moved outwardly in their respective slots 49 and 50 to the position indicated in dotted outline in Fig. 2, which shows the holder 54 at the completion of its outward movement. This movement is effected by a stationary cam 64 upon which rides a pair of rollers 65, one carried by each of the holders 54 and 55, the cam 64 being suitably supported upon the standard 28. It will be apparent from this description that the holders are each capable of independent movement toward the periphery of the wheel 38 and are also capable of independent rotary movement upon the shaft 33 during the rotation thereof within the limits of the slots 49 and 50 of the wheel 38, and are prevented from moving longitudinally of the shaft by the inner vertical wall 53 of the wheel at one side and upon the other by the oppositely disposed vertical face of the cam 64 (Figs. 3 and 7). The independent rotary movement of the holders with respect to the shaft 33 will be described shortly hereinafter. A knife 68, which is best shown in Figs. 3, 4, 5 and 6, is carried upon the shouldered end 56 of each of the knife holders 54 and 55, the knives each being provided with a projecting portion 69 fitting in a slot formed in its respective holder and secured in position thereon by a pair of screws 70. The knives and the supporting portions 56 of the holders are slotted at their outer ends as indicated at 71 (Fig. 6), the slots being centered with the groove 39 of the wheel 38 so that as the knife holder is moved outwardly, as hereinbefore described, the wires spanning either of the

slots 49 and 50 will be entered within the slot 71, as clearly indicated in Fig. 3. The slot 71 in the portion 56 of the holders is of a width which is substantially the same as the diameter of the insulated wires, thereby serving as a guide for the wire. The extreme outer end of the slot in the knives is provided with a tapered portion 72 for the purpose of guiding the conductors and upon which the cutting edges are formed, the groove 39 of the wheel 38 being similarly tapered. As either of the knives are moved into the slots 49 or 50 of the wheel 38, the conductors are first centered with respect to the balance of the slot 71 in the knife and the slot in the portion 56 of the holder due to the tapered cutting portion 72 of the knife. The balance of the slot 71 of the knife has parallel sides and is of such a width that the conductor core 5 may be entered therein without injury, it being centered therewith due to the guide slot 71 formed in the portion 56 of the holder, as hereinbefore described. The cutting edges 72 of the slot 71 during their movement past the conductors serve to partly sever the insulation thereof, as will readily be apparent, and upon reaching their full outward movement as shown on Figs. 3, 4 and 6, the core will be entered in the narrow upper portion of the slot 71 with only two very small diametrically opposed portions of the insulation unsevered.

Pivotedly supported upon the vertical wall 53 of the rotary wheel 38 at diametrically opposite points is a pair of triangular shaped plates 75 and 76, one associated with each of the knife holders. The plates 75 and 76 are carried upon posts 77 fixed to the wall 53, as clearly indicated on Fig. 7, and are positioned outside of the wheel 38 and around the periphery of the cam 64, the sides of the plates adjacent the cam 64 being arc shaped. The plates 75 and 76 are normally maintained in the positions shown in Fig. 2 during each rotation of the wheel 38, except as will be shortly described, with a short corner face engaging the periphery of the associated roller 65 and their opposite substantially parallel faces engaging pins 78 fixed in the wall 53 of the wheel 38. As hereinbefore described, the spring plungers 62 serve to maintain the knife holders 54 and 55 in the position shown in Fig. 2 with the shouldered ends 56 against one side of the slots 49 and 50, and the rollers 65 in turn carried upon the holders 54 and 55 maintain the plates against the pins 78. Secured to the bracket 28 near the base plate 27 is a stationary cam 80 having advancing and receding cam faces 81 and 82 upon which corners 83 of the plates 75 and 76 ride during the rotation of the wheel 38. In the position of the apparatus, as shown in Fig. 2 and as hereinbefore described, the knife 68 has completed its outward movement and has severed the insulation of the

conductors at diametrically opposite points (Figs. 4 and 6), and in the continued rotation of the wheel 38 the complete severing and stripping or pushing back of the insulation upon the conductor cores will be affected. In the position of the parts as just noted, it will be observed that the corner 83 of the plate 75 has just engaged the advancing cam surface 81 of the cam 80, and in the continued rotation of the wheel 38 with the corner 83 riding up the cam surface 81 that the plate 75 will be rocked clockwise about its pivot post 77, and consequently due to the engagement thereof with the roller 65 the knife holder 54 and its knife 68 will also be rocked clockwise about the shaft 33 against the action of the associated spring pressed plunger 62. This movement will continue until the corner 83 of the plate 75 rides upon the receding cam surface 82. The extent of the movement of the knife 68 in a clockwise direction while the wheel 38 is continuing its counter-clockwise rotation is best shown in Fig. 5, which clearly shows the insulation of the conductors completely severed and stripped or pushed back upon the conductor cores leaving them bare. It will be understood that during the skinning operation the conductors are still gripped to the wheel 38 by the plungers 40 at either side of the slot 49, and that the other knife holder and associated knife 68 will still hold the position shown in the drawings relative to the wheel 38. As the plate 75 rides down the cam surface 82 after the stripping operation, the spring plunger 62 serves to return the associated knife holder and plate 75 to their normal positions, the plate against the associated stop pin 78 and the shouldered portion 56 of the holder against one side of the associated slot in the wheel 38. In unison with this latter movement, the roller 65 is riding down the receding surface of the cam 64 and is held in contact therewith by the compression spring 60, so that when the wheel 38 has rotated 180° from the position shown in Fig. 2 the knife 68 carried by the holder 54 will have been drawn inward in the slot 49 to the position in which the knife 68 carried by the holder 55 is shown.

The apparatus 26 for taking up the stripped conductors 12 as delivered from the stripping apparatus will now be described in detail. A bracket 83 secured to the base plate 10 is provided with a plurality of horizontally disposed journals 84, 85, 86 and 87. Carried by the journals 86 and 87 is a reciprocal and rotatable arbor 88 which has splined thereto, as indicated at 91, a grooved pulley 92, receiving motion from a similar pulley 93 of larger diameter fixed to the shaft 33 of the stripping apparatus through a belt 94, the belt traveling in the direction indicated by the arrow. Secured to a hub of the pulley 92 and abutting the adjacent vertical face of

the journal 86 is a gear 95, the axis of which is the arbor 88 upon which it freely rotates. Meshing with the gear 95 is a gear 96 secured to a reverse screw threaded shaft 99 rotatably supported in the journals 84 and 85. The shaft 99 forms part of a distributing or traversing mechanism of a well known type indicated generally by the numeral 100, which it is believed will not need any further description, since this type of mechanism is well known in the art of strand coiling. Fixed to the upper end of the arbor 88, as viewed in Fig. 1, is a collar 101 provided with a circular channel 102 within which extends an operative connection 103 from the mechanism 100. A take-up reel 104 is secured to the arbor 88 by a hand nut 105 screw threaded upon the arbor 88, the nut serving to clamp the reel 104 against a collar 106 which is fixed to the arbor 88. As the shaft 33 rotates in a counter-clockwise direction it will be apparent that the arbor 88 will be rotated in a similar direction and through the gears 95 and 96 the reverse screw threaded shaft 99 will be rotated in a clockwise direction to reciprocate the mechanism 100 thereon, the operative connection 103 and collar 101 transmitting such motion to the rotating arbor 88 carrying the reel 104, thus causing the stripped conductors to be wound upon the reel 104 in even layers.

The operation of the apparatus it is believed will be clearly apparent from the foregoing description, but briefly stated is as follows: Assuming that a supply reel 11 of conductors to be stripped and an empty take-up reel 104 have been properly positioned upon the arbors 13 and 88, respectively, and the conductors properly threaded from the reel 11 and around the wheel 38 and secured to the reel 104, the shaft 33 carrying the wheel 38 is caused to rotate. As the wheel 38 rotates in the direction indicated by the arrow in Fig. 2, the conductors are guided from the left hand roller 35 (Fig. 2) and into the groove 39 of the wheel 38, it being understood that the spring pressed plungers 40 are in a retracted position between the radially extending dotted lines 108 shown upon the face cam 41 between which points the low point of the cam occurs (Fig. 1). While the knife holder 55 is being rotated from the position shown in Fig. 2 to the position in which the knife holder 54 is shown, it is moved outwardly, as hereinbefore explained, due to the roller 65 carried thereby riding upon the advancing surface of the cam. This causes the knife 68 carried by the holder 54 to move into severing engagement with the insulation of the conductors within the slot 49, as clearly indicated in Fig. 4. The wheel 38 in continuing to rotate brings the corner 83 of the plate 76 onto the advancing cam face 81, and thereby rocks the plate 76 clockwise about its pivot and the knife consequently

in a direction reverse to that in which the wheel is moving while the conductors which are clamped to the wheel are drawn through it, thus moving the insulation back along the conductors. Upon the corner 83 of the plate 76 riding onto the receding cam surface 82 of the cam 80, the spring pressed plunger associated with the knife holder 55 will cause the latter to assume its normal position against one side of the slot 49, and in unison therewith it is moved inwardly through the energy of the spring 60 as the roller 65 rides upon the receding surface of the cam 64. In the further rotation of the wheel the spring plungers 40, in succession, release their grip upon the conductors upon reaching the right hand point 108 of the cam face 41 (Fig. 2), the conductors passing around the right hand roller 35 (Fig. 2) and thence are taken up upon the reel 104 in the manner hereinbefore described.

During the actuation of the holder 55 and its associated knife 68, as just described, the other holder 54 and its knife 68 which are shown at the completion of the severing operation will be actuated in the manner described in connection with the holder 55 and its knife 68 to strip the conductors and return to their normal position relative to the wheel 38 and thence with the wheel 38 to the beginning of its cycle at a point intermediate the guide rollers 35 at the upper surface of the wheel 38.

Due to the well balanced construction of the apparatus and the constant speed at which it is operated, the twisted conductors to be stripped will be drawn from the supply reel at a substantially constant speed with a substantially uniform tension. This allows the apparatus to be operated at a high rate of speed, and with the stripping of the insulation from the conductors along two spaced portions thereof for every revolution of the wheel 38 the output is very great.

While the apparatus is here shown as operating upon a pair of twisted conductors, it will be obvious that the apparatus is equally well adapted to strip either a greater number of conductors similarly twisted or a single conductor.

What is claimed is:

1. In an apparatus for stripping a covered strand, continually moving means for drawing a strand from a supply at a substantially constant speed, means carried by the drawing means for severing the covering of the strand at predetermined points throughout the length thereof and moving the covering back upon the strand for a predetermined distance, and means for causing the operation of the severing means at each of the predetermined points during the continued movement of the drawing means.

2. In an apparatus for stripping a covered strand, rotary means for drawing a strand from a supply at a substantially constant

speed, means carried by the drawing means designed first to move radially thereof to cause a severing of the covering of the strand at predetermined points throughout their length and secondly to move in a direction reverse to the direction of rotation of the drawing means to move the covering back upon the advancing strand for a predetermined distance, and means for causing the said movements of the severing means in timed sequence during the continued rotation of the drawing means.

3. In an apparatus for stripping a covered strand, a rotary drum for drawing a strand from a supply at a substantially constant speed, said drum provided with a peripheral groove within which the strand is clamped for causing it to move with the drum, means for clamping the strand within the groove during a predetermined rotary movement of the drum, means associated with the drum for severing the covering of the strand at predetermined points throughout the length thereof and moving the covering back upon the strand for a predetermined distance, means for operating the severing means during the continued movement of the drum, and means for causing the operation of the clamping means to clamp the strand to the drum and release the strand therefrom and for operating the severing means in timed sequence during the continued rotation of the drawing means.

4. In an apparatus for stripping a covered strand, a slotted knife member for severing the strand covering, means for causing a continuous relative movement between the strand and the member, and means operating at predetermined intervals during said relative movement to cause the edges of the slot in the knife member to engage and thereby sever the strand covering at predetermined points along the strand.

5. In an apparatus for stripping a covered strand, means for severing the strand covering, means for causing the strand and the severing means to advance simultaneously along a predetermined path, and means for causing the severing means to engage and thereby sever the strand covering and for thereafter causing the severing means to move in a reverse direction along the path to move the covering along the strand for a predetermined distance and thereafter resume its forward movement.

6. In a wire skinning machine, a rotatable drum, a series of knives movably mounted on said drum, a cam, means for feeding insulated wire over said drum, and means for rotating said drum to cause said cam to move said knives in a direction opposite to that of the drum for removing the insulation from said wire at predetermined intervals.

7. In an apparatus for stripping a covered strand, means for drawing a strand from a

supply, means cooperating with the drawing means for severing the covering of the strand at predetermined points throughout the length thereof and moving the covering back upon the strand in a direction opposite to the directional movement of the strand for a predetermined distance, and means for operating the severing means at each of the predetermined points during the drawing of the strand from the supply.

8. In a wire skinning machine, a drum mounted on a rotatable shaft, a plurality of skinning knives movably mounted on said drum, a cam, means for feeding insulated wire over said drum, means to rotate said shaft and said drum to cause said cam to move said knives for removing the insulation from said wire at predetermined intervals, and means for preventing said cam from being rotated when said shaft is rotated.

9. In a wire skinning machine, a plurality of skinning knives, means for feeding insulated wire through said knives one after another, and means for moving said knives in a direction opposite to the movement of the wire along the surface of the wire while the wire is moving to strip a section of insulation therefrom.

10. In a wire skinning machine, a plurality of skinning knives, means for feeding insulated wire through said knives one after another, and means for moving said knives in a direction opposite to the movement of the wire along the surface of the wire while the wire is moving to strip sections of insulation therefrom, said last means consisting of a cam which moves said plurality of knives one after another.

11. In a wire skinning machine, a plurality of movable knives, means for feeding insulated wire through said knives one after another, an operating member, and means for moving said knives in the direction of the movement of the wire to cause said operating member to move said plurality of knives one after the other in a direction opposite the direction of movement of the wire for stripping a section of insulation from said wire.

12. In a wire skinning machine, a rotatable drum carrying a plurality of movable skinning knives, a cam for moving said knives, a spool carrying a supply of insulated wire, a second spool for receiving wire, means for rotating said second spool to pull said wire from the supply spool over said drum, and means for rotating said drum to cause the cam to move said knives to strip the insulation from said wire at predetermined intervals.

13. In a wire skinning machine, a rotating drum, a plurality of movable skinning knife assemblies on said drum, means for feeding insulated wire over said drum and through said knife assemblies, and a cam for moving said knife assemblies to remove strips of in-

- sulation from said wire at predetermined intervals while said wire is moving, said knife assemblies including members for moving said assemblies in a direction opposite to the direction of the movement of the wire.
14. In a wire skinning machine, a rotating drum, a plurality of movable skinning knife assemblies on said drum, means for feeding insulated wire over said drum and through said knife assemblies, and a cam for moving said assemblies to remove strips of insulation from said wire at predetermined intervals while said wire is moving, said knife assemblies including members for moving said assemblies in a direction opposite to the movement of the wire, one of said members carrying adjustable knife blades.
15. In a wire skinning machine, a plurality of movable skinning knives and an operating member, a spool carrying a supply of insulated wire, a second spool for receiving wire, means for rotating said second spool to pull said wire from the supply spool and through said knives, and means for moving said knives to cause said member to again move said knives to strip sections of insulation from said wire at predetermined intervals.
16. In a wire skinning machine, a plurality of movable skinning knives, an operating member, a spool carrying a supply of insulated wire, a second spool for receiving wire and for pulling said wire from said supply spool and through said skinning knives, means for leading said pulled wire through said plurality of knives one at a time, means for rotating said second spool, and means for moving said knives to cause said member to again move said knives one after another to remove strips of insulation from said wire at predetermined intervals.
17. In a wire skinning machine, a plurality of movable skinning knives, an operating member, a spool carrying a supply of insulated wire, a second spool for receiving wire, means for rotating said second spool to pull the wire from said supply spool and through said skinning knives, means for leading said pulled wire through said plurality of skinning knives one at a time, and means for moving said knives to cause said operating member to again move said knives one after another in a direction opposite to the direction of the first movement of the knives to strip sections of insulation from said wire at predetermined intervals.

In witness whereof, I hereunto subscribe my name this 25 day of March A. D., 1926.

JOHN STANLEY STULL
